Primary Examiner — Clare E Heflin(74) *Attorney, Agent, or Firm* — Lucas & Mercanti, LLP(57) **CLAIM**

The ornamental design for a lighting fixture, as shown and described.

DESCRIPTION

FIG. 1 is a top, front perspective view of the design;
 FIG. 2 is a bottom, rear perspective view thereof;
 FIG. 3 is a top plan view thereof;
 FIG. 4 is a bottom plan view thereof;
 FIG. 5 is a front elevation view thereof;
 FIG. 6 is a rear elevation view thereof;
 FIG. 7 is a right side elevation view thereof; and,
 FIG. 8 is a left side elevation view thereof.
 The broken lines on top of the lighting fixture are included for environmental purposes only and form no part of the claimed design.
